UNITED STATES PATENT OFFICE.

LEE P. HYNES AND PERCY M. GRIFFIN, OF ALBANY, NEW YORK, ASSIGNORS TO CONSOLIDATED CAR-HEATING COMPANY, OF ALBANY, NEW YORK, A CORPORATION OF WEST VIRGINIA.

SAFETY SWITCH.

Application filed March 19, 1920. Serial No. 367,256.

To all whom it may concern:

Be it known that we, LEE P. HYNES, a citizen of the United States, residing at Albany, in the county of Albany and State of New York, and PERCY M. GRIFFIN, a citizen of the United States, residing at Albany, county of Albany and State of New York, have invented certain new and useful Improvements in Safety Switches, the following being a full, clear, and exact disclosure of the one form of our invention which we at present deem preferable.

For a detailed description of the present form of our invention, reference may be had to the following specification and to the accompanying drawings forming a part thereof, wherein—

Fig. 1 is a vertical longitudinal section of our device, and
Fig. 2 is a plan thereof with the cover reversed.

Our invention relates to electric switches having the following provisions for safety. The cover of the enclosing box can not be opened when the switch is in its "on" position, the contacts being then closed and the current flowing. The operating handle extends through a slot in the box and that slot is automatically covered by a plate which 30 the handle draws down over the slot when moved to "on" position. The cover of the box is in two sections, one of which is hinged and contains the slot traversed by the handle. The opening of this hinged section, after 35 the handle has been moved to "off" position exposes the replaceable fuse, but does not expose the live terminal, through which the current reaches the switch.

Referring to the drawings, A and B, which are shown in dotted lines in Fig. 2 represent the two contacts of the switch, the separation or engagement of which causes the opening or the closing of the circuit to be controlled, such, for instance, as the circuit leading to an electric heater. B is the stationary contact and A is the one to be moved away from or brought into contact with B. The two contacts are contained within an arc-chute C formed of insulating material and in the shape of an open-ended box or tube. The chute C is located between the two pole pieces D and D¹ of a blow-out magnet E which has the well known function of extinguishing any arc

which may occur between contacts A and B 55 when they are separated at a time when current is flowing between them.

The switch itself is of a well known "snap" type formed by two overlapped U levers F and G. The lever F is pivoted near its left 60 hand end by pivot-pins f, f to the vertical plates or standards K, K and at its opposite or yoke end is secured one end of a curved spring A¹ which at its opposite end carries the aforesaid contact A. The lever G is 65 larger than F and encloses it, being pivoted near its right end by pivot-pins g, g to the aforesaid standards K, K. A spring H is connected to the yoke end of lever G and to a rod f² near the yoke end of lever F. 70 When the parts of this switch are in the normal closed condition, the lever G is depressed at its outer (left) end as shown in Fig. 1, and the lever F is nearly horizontal with contact A down on contact B. The 75 spring H then lies below the pivotal points g, g of lever G and tends to hold the contacts A and B in engagement. When, however, the left end of lever G is lifted, it brings the line of spring H above said points 80 g, g and its tension acts to swing the lever F upward at its right end to suddenly separate contacts A and B. This type of switch is well known and not of our invention. The described parts are mounted on an insulating 85 base plate M on the floor of the metal box, P, P, P. The live terminal of the circuit is connected to contact B by means of the connector X at the rear of the arc-chute C, this connector X being the only exposed 90 "live" point in the apparatus, when the box is open. From the contact A the current passes by wire 1 and connector 2 to the coil of the blow-out magnet E and thence by wire 3 and connector 4 to the pole pieces 95 and core of the magnet. On the flat out-turned base of pole piece D¹ is adjustably mounted, by means of slot d, a fuse clip T between which and a similar clip T¹ is the fuse W. From fuse W the current is conducted to the electric heater, or other consumption device.

The top of the box is divided transversely at the hinge Q into two parts, the part Q² at the right of the hinge being permanently 105 secured to the box and the part Q¹ at the left thereof being free to be lifted and swung upwards and backwards under certain con-

ditions. In the part Q^1 is a longitudinal slot through which passes the insulating handle R of the switch. The handle R is secured to the aforesaid lever G of the switch 5 and has an enlargement R^1 at its upper end. It also passes through a short opening g in a slide Q^3 which moves to and fro with the handle just inside the box top and forms a cover for the slot in which the handle R 10 travels. Therefore when the switch is closed and the handle R is in the upright position shown by full lines in Fig. 1, the slot is closed to prevent any access to the switch by a wire or other piece which, but for the 15 slot-cover Q^3 might be thrust into the box through the slot. When the handle R is moved into the position shown in the dotted lines of Fig. 1 to open the switch, the slot-cover Q^3 does not prevent such movement 20 of the handle, but slides back together with it, being upheld and directed by the guide-plate Q^4 on the fixed part of the cover.

It will be evident that when the switch is closed, the metal parts thereof being in circuit and "alive," those metal parts are 25 wholly inaccessible from outside the box, since the hinged cover Q can not be raised because the enlargement R^1 on the handle will not pass through the slot in said cover. 30 The cover may also be padlocked by means of the lips J, J , but even when unlocked it can not be lifted unless the switch is first opened by moving handle R to its dotted-line position. When the switch is thus open, 35 the only live part is the contact B and its connector X which can not be reached by a person's hand even if the cover Q^1 is up. Moreover, when the switch is open a lug S^1 on the aforesaid lever G comes under a lip S^2 40 on the aforesaid lever F . Hence the lever F , (which it will be remembered carries the contact A), can not be pressed down to close the contacts A and B while the cover Q^1 is open. The lug S^1 is then in line with the 45 pivotal point g of lever G and pressure thereon by lip S^2 will merely press against the pivotal point g and not exert any turning movement on lever G nor allow lever F to descend. Only when the handle R is 50 turned to the left subsequent to the closing of the cover Q^1 , removing lug S^1 from under lip S^2 and bringing the spring H below the dead-center-line will the switch close. At the same time the fuse W will be easily accessible 55 when the cover Q^1 is lifted, and, by virtue of the adjustable clip T , the apparatus may be set to receive a fuse of any desired length. But the fuse can be taken out and replaced only when the switch is open 60 and in a perfectly safe condition.

It will be observed that we secure a snap action in closing as well as in separating the contacts A and B , since the spring-actuated lever F is capable of movement independently of the handle R and the lever G . For

this reason, unless some preventative means is provided it would be possible for a person inspecting the open box, or replacing a fuse, to accidentally press down the lever F and thereby bring contact A against contact B 70 receiving, in consequence, a shock from the live contact B through the movable contact A to which lever F is connected. This explains the importance of having lever F locked individually by the lug S^1 and the 75 lip S^2 when the switch is open.

The arc-chute C is readily removable by unscrewing the side plates Y, Y , the bottom of the chute being formed by the slate base M . 80

What we claim as new and desire to secure by Letters Patent is:

1. The combination with an electric switch of an enclosing box therefor provided with a hinged cover, a switch handle engaging 85 said cover and having a portion so positioned as to prevent opening of the cover when the circuit through the switch is closed, and means supported independently of the cover for preventing movement of the switch parts 90 when the cover is open except by movement of the handle.

2. The combination with an electric switch having a handle and members capable of movement independently of the handle, an 95 enclosing box for the switch provided with a movable cover, said switch handle and said cover having complementary means for preventing opening of the cover when circuit through the switch is closed, and means actuated by movement of the handle to engage 100 one of said switch members when the handle is moved to open position.

3. The combination with an electric switch having a handle and members capable of 105 movement independently of the handle, an enclosing box for the switch provided with a movable cover, said switch handle and said cover having complementary means for preventing opening of the cover when circuit through the switch is closed, and a locking lug carried by the handle and positioned to engage 110 one of said switch members when said handle is moved to open position.

4. The combination with an electrical 115 switch having a handle and switch members capable of movement independently of the handle, an enclosing box for the switch members having a movable cover, said handle and said cover having complementary 120 means for preventing opening of the cover when the circuit through the switch is closed, an overhanging lip on one of said switch members, and a locking lug carried by said handle and positioned to engage said 125 lip.

5. The combination with an electric switch having two relatively movable actuating members, of an enclosing box for said switch having a movable cover, means connected 130

with one of said members for preventing opening of the cover while the circuit is closed through the switch, and means for preventing movement of the switch independently of a closing movement of the cover after the latter has been moved to open position.

6. The combination with an electric switch having two relatively movable actuating members, of an enclosing box for said switch having a movable cover, means connected with one of said members for preventing

opening of the cover while the circuit is closed through the switch, and complementary abutment members on said actuating members so positioned as to be placed in engagement as the said actuating members are moved to open position. 15

Signed at Albany, county of Albany, State of New York, this 17th day of March, 20 1920.

LEE P. HYNES.
PERCY M. GRIFFIN.
